UNITED STATES PATENT OFFICE.

GEORGE A. FARLEY, OF LAWRENCE, MASSACHUSETTS.

DRAWING MECHANISM FOR SPINNING-MACHINES.

No. 872,804.

Specification of Letters Patent.

Patented Dec. 3, 1907.

Application filed May 2, 1907. Serial No. 371,402.

To all whom it may concern:

Be it known that I, GEORGE A. FARLEY, of Lawrence, county of Essex, State of Massachusetts, have invented an Improvement in Drawing Mechanism for Spinning-Machines, of which the following description, in connection with the accompanying drawings, is a specification, like characters on the drawings representing like parts.

In spinning frames, having the usual three sets of parallel drawing rolls, it is necessary to adjust the distance between the front and middle drawing rolls according to the length of the staple. With certain adjustments of these rolls, much difficulty is often experienced with what is termed as "lapping", due to the breaking of the roving while it is being drawn out between the middle and the front rolls, and the subsequent winding of the broken end and succeeding roving about the lower middle roll. I have observed that the nearer the two lower rolls are adjusted, the less likely is this difficulty to occur, for the reason that the front lower roll is more likely to pick up the broken end and carry it along when it is running close to the lower middle roll than when running at some distance therefrom. I have discovered that if the stretch or length of roving between the points at which it is held is increased without increasing the distance between the lower rolls, the difficulty of lapping will be, in a large measure, avoided.

In practice the lower rolls are of steel and are positively driven by gearing at their ends, while the upper rolls are of leather and run idle. In order to vary the distance, therefore, between the lower rolls it is necessary to change the location of the driving gears, which is a matter of some difficulty and involves stopping the machine while the adjustment is being made.

The ordinary gang of drawing rolls is provided with a thread guiding means, usually called the traverse rod, through which the threads pass, said rod being moved longitudinally back and forth at a slow speed, so as to cause the threads to pass between the drawing rolls at different points and preventing the tendency to wear grooves therein, which would otherwise be caused. In order to guide the threads properly this rod is located in the rear of, and closely adjacent the rear pair of rolls, the distance at which the rod should be held from the rolls having been determined by experience, which distance

must be maintained in order that satisfactory results may be secured.

The object of my invention is to provide means whereby the rolls may be relatively adjusted for long or short stock without changing the relative positions of the lower front and middle rolls, so that they may always be run close together, and without varying the distance between the traverse bar and the point of engagement between the rear rolls, and, further, without in any way disturbing the driving gears, or stopping the machine. I accomplish this object by the means shown by the accompanying drawing, in which,

Figure 1 is an end elevation of the drawing roll stand provided with my invention. Fig. 2 is a section on line 2-2 of Fig. 3, showing the parts in a different position of adjustment from Fig. 1. Fig. 3 is a plan view of a series of drawing rolls including two adjacent stands provided with my invention. Fig. 4 is a detail view of the traverse rod reciprocating mechanism. Figs. 5 and 6 are, respectively, sectional views on the lines 5-5 and 6-6 of Fig. 3.

The stands *a* are of ordinary form having open bearings *a'* formed therein for the lower front roll *b*, and a bearing piece *c* is secured to the upper side of each stand *a* and may be made integral therewith, so far as my invention is concerned, and preferably is made integral therewith in most instances, although in some instances it may be desirable to adjust it thereon. Each bearing piece *c* is provided with open bearings *c'*, *c''* for the middle and back lower rolls *d* and *e* respectively. Said rolls *b*, *d* and *e* are driven by intermeshing gears in the usual manner, as indicated in Fig. 1. A bracket *f*, comprising a flat plate, having a transverse slot *f'* at its front end and a pivot slot *f''* in the middle thereof, is adjustably secured to the upper side of each bearing piece *c* by suitable means, as a clamping bolt *g* which passes through a slot *f'''* formed in the plate and is threaded in the bearing piece *c*, permitting adjustment of the bracket *f* thereon towards and from the rolls.

A thread guiding rod *x*, called the traverse rod, is slidably mounted in the slots *f'* of brackets *f*, said rod being provided with the usual thread guiding apertures *x'* and being disposed closely adjacent the rear rolls as shown. The means shown for reciprocating the rod is not substantially different from means already known in the art and com-

prises a pair of depending arms x^2, x^3 , which are mounted on rod x and engage opposite sides of a cam y , mounted on a shaft z , said shaft being journaled in an adjacent stand a and having a worm wheel w thereon which engages a worm e' formed on the lower back roll e , so that when the roll e is rotated said rod will be slowly reciprocated.

A series of cap bars are pivotally mounted in the slots f^2 of brackets f by means of pivot bolts h' which rest therein. The cap-bar, shown in Fig. 3, is shown as comprising a series of three roll holding arms i, i', i^2 , although five arms are frequently employed, the end arms i, i^2 being provided at their adjacent sides, and said middle bar i' at each side with bearing slots i^4 , each slot being open at its upper end and adapted to receive loosely the middle and back upper rolls j and k respectively. Extension pieces m, m', m^2 are adjustably connected to the end portions of the arms i, i', i^2 , respectively, in a manner well known in the art, a slot and bolt connection being employed, as shown, which is readily accessible from the upper side of the arms. Said extension pieces are also provided with open roll holding slots m^4 , similar to, and similarly arranged to slots i^4 and in which the upper front rolls n are located.

In Fig. 1 the parts are shown as adjusted for a short staple, that is, the front and middle lower rolls are so held that they run together as closely as practicable, and, when they are adjusted in this position, practically no difficulty from lapping is experienced. In this position the upper rolls bear on the corresponding lower rolls at approximately the points of common tangency, so that the thread or roving r is drawn straight as it passes from the rear to the front rolls. If it is desired to adjust the two front sets of rolls for a longer staple, that is, to increase the length of the roving between the point at which it is held and the point at which the drawing pull is applied, so that single fibers will not be simultaneously engaged and consequently broken, the clamping bolts g' of each of the brackets f are loosened and pushed back, carrying the cap-bars and top rolls with them, to the extent which it is desired to increase said length. The top rolls will then no longer bear upon the lower rolls at the points of common tangency, but on points in the rear thereof, so that, to make this adjustment effective, the extension pieces m, m', m^2 are then adjusted forwardly, so that the front upper rolls are held in the position of common tangency again, and the adjusted parts are in the position of Fig. 2. The middle and back upper rolls will be in a lower position with relation to the cap-bar, when in the position of Fig. 2, than when in that of Fig. 1, but the length of roving drawn at one time or the distance between the points of rolling contact of the middle and front rolls

is thus increased to the desired extent without changing the positions of the lower rolls, so that, in this position of adjustment, if the roving should break the broken end portion will be picked up by the lower front roll.

The rearward adjustment of the bracket f also carries the traverse rod x rearwardly, its driving connection with the lower rear roll not being interfered with by this movement, as the fingers x^2, x^3 , may be moved transversely of the face of the cam y for some distance without being moved out of engagement therewith. The result is that the thread is guided at the same distance from the points of rolling contact between the upper and lower rear rolls, as it was before the parts were adjusted, so that the roving will be guided back and forth between these rolls as advantageously as it was before. Moreover the traverse rod is necessarily located so close to the rear rolls that adjustment to an extent which is usually necessary would carry the upper roll back against the traverse rod or so close thereto as to interfere with the proper working thereof, so limiting the range of adjustment that the above described adjusting means would otherwise be of little practical value.

It will be understood that all of the cap-bars on one side of a frame will be adjusted practically together, so that adjustment of the brackets will move the whole series of cap-bars the same extent. As the lower rolls are in no way disturbed by the above described adjustment, the adjustment may be made without stopping the machine or breaking the roving. Moreover as the operator is enabled to make the adjustment while the machine is running it is possible to find, with the utmost readiness, the exact point to which the rolls should be adjusted.

Having thus described my invention, what I claim as new and desire to secure by Letters Patent is:

1. The combination of a support having a parallel series of upper and lower drawing rolls, bearings in which said lower rolls are mounted, and means for driving said lower rolls, cap-bars for holding the upper rolls in position over said lower rolls, said bars having extensible portions between said upper rolls to permit relative transverse adjustment thereof, a thread guiding rod, and brackets to which said cap-bars are pivotally connected and in which said guiding rod is slidably mounted, said brackets being mounted on said support and having an adjustable connection therewith permitting adjustment thereof transversely of the rolls, substantially as described.

2. The combination of a support having a parallel series of upper and lower drawing rolls, bearings in which said lower rolls are mounted, and means for driving said lower rolls, cap-bars for holding the upper rolls in

position over said lower rolls, said bars having extensible portions between said upper rolls to permit relative transverse adjustment thereof, a thread guiding rod, brackets to 5 which said cap-bars are pivotally connected and in which said guiding rod is slidably mounted, said brackets being mounted on said support and having an adjustable connection therewith permitting adjustment 10 thereof transversely of the rolls, and means

for reciprocating said rod permitting transverse adjustment thereof, substantially as described.

In testimony whereof, I have signed my name to this specification, in the presence of 15 two subscribing witnesses.

GEORGE A. FARLEY.
